UNITED STATES PATENT OFFICE.

HENRY BERNSTEIN, OF PHILADELPHIA, PENNSYLVANIA, ASSIGNOR TO
BERNSTEIN, KAUFMAN & CO., OF SAME PLACE.

DESIGN FOR TRIMMING.

SPECIFICATION forming part of Design No. 25,818, dated July 21, 1896.

Application filed May 19, 1896. Serial No. 592,227. Term of patent 3½ years.

To all whom it may concern:

Be it known that I, HENRY BERNSTEIN, a citizen of the United States, residing in the city and county of Philadelphia, State of Pennsylvania, have invented and produced a new and original Design for Trimming, of which the following is a specification, reference being had to the accompanying drawings, forming part thereof.

10 The leading feature of my design for trimming is a tubular body with crossed cords on the surface thereof.

Figure 1 represents a side elevation of a piece of trimming embodying my design.

15 Fig. 2 represents an end view thereof.

In the drawings, A designates the body of a piece of tubular trimming. On the surface of said body are crossed cords B of a fluffy nature and crossed cords C of a crimped nature, said cords B and C alternating. 20

What I claim is—

The design for trimming substantially as described and shown.

HENRY BERNSTEIN.
